UNITED STATES PATENT OFFICE

HERMAN H. HEIDBREDER, OF QUINCY, ILLINOIS, ASSIGNOR TO THE QUINCY STOVE
MANUFACTURING COMPANY, OF QUINCY, ILLINOIS, A CORPORATION OF ILLINOIS

DESIGN FOR A GAS RANGE

Application filed June 4, 1931. Serial No. 40,075. Term of patent 7 years.

To all whom it may concern:

Be it known that I, HERMAN H. HEIDBREDER, a citizen of the United States, residing at Quincy, county of Adams, and State of Illinois, have invented a new, original, and ornamental Design for Gas Range, of which the following is a specification, reference being had to the accompanying drawing, forming part thereof.

The figure is a perspective view of the gas range, showing my new design.

I claim:

The ornamental design for a gas range, as shown.

HERMAN H. HEIDBREDER.
